UNITED STATES PATENT OFFICE

2,574,561

WRITING INSTRUMENT

Herbert N. Hagel, Forest Hills, N. Y., assignor to
 Everlast Pen Corporation, New York, N. Y., a
 corporation of New York

Application May 11, 1950, Serial No. 161,359

1 Claim. (Cl. 40—28)

1

The present invention relates to a writing instrument, and more particularly to an inexpensive writing instrument which may be used as an advertising medium.

An object of the present invention is to provide a writing instrument such as a mechanical pencil wherein the empty tubular barrel connected to the writing mechanism of the pencil may be utilized for displaying miniature containers or packages of standard brand products, such as for example, bottles of beer, milk, whiskey, or products packaged in cans or cartons.

A small miniature replica of automobiles, trucks or novelty figurines may also be used as an advertising medium or a novelty respectively.

Another object of the invention is to provide a preferably plastic transparent barrel connected to the writing end of the pencil wherein a pair of miniature objects may be alternately displayed or revealed by the gravity movement of an opaque sliding sleeve which covers and uncovers the objects one at a time by alternately holding the instrument in the writing or inverted position and when the sliding sleeve comes to rest, the transparent tubular barrel portion above the sliding sleeve becomes a window for displaying the figurine therein.

The window, which is preferably tubular when uncovered by the sliding sleeve admits the light from all directions, and since the barrel of the writing instrument is preferably tubular a certain amount of magnification is had when the figurine is viewed.

The sliding gravity sleeve for alternately covering and uncovering the windows may or may not have advertising matter printed thereon and preferably have a finish simulating the finish of the mechanical body portion of the writing end of the instrument.

The sliding gravity sleeve for covering and uncovering the window may quickly slide in the hollow transparent barrel by gravity alone or it may be retarded by having the transparent barrel filled with a desirable retarding substance such as oil.

The figurines within the transparent plastic barrel are each separately or integrally mounted to a connecting rod, and the figurines and connecting rod as a unit may be loosely placed within the transparent barrel.

The connecting rod is preferably of a diameter in cross section equivalent to the inside diameter of a plastic guiding sleeve which is interposed between the gravity sliding sleeve and the figurines; but loose enough to hold the figurines in

2

a co-axial relation to the barrel and at the same time permit the figurines to rotate. A design application showing a suitable pair of figurines is concurrently filed with this mechanical application.

Other objects and advantages of the present invention will be obvious as brought out in the following specification.

Reference will be had to the accompanying drawing forming a part of this specification in which similar reference characters indicate corresponding parts thru-out the several views, in which,

Fig. 1 is a front view of the present invention, 15 showing the writing instrument in the writing position with one of the figurines displayed in the window adjacent the top of the instrument,

Fig. 2 is a rear view, showing the writing instrument in the inverted position with the other 20 figurine displayed in the window adjacent the writing mechanism of the instrument,

Fig. 3 is an enlarged vertical section thru the writing instrument, showing the structure of the transparent barrel and operating parts; and

Fig. 4 is an enlarged section taken on the line 25 4—4 of Fig. 3.

Referring to the drawings, wherein I have shown by way of illustration merely, a writing instrument 10 which may be a ball pen, or mechanical pencil having the usual or conventional barrel portion 11 and tapered operating piece 12 containing the ball pen or mechanical pencil units, and a preferably transparent plastic barrel 13 which is secured to the barrel portion 11.

The transparent tubular barrel 13 has a solid top portion 14 which is flattened down to secure the usual band 16 in the groove 15 for fixing thereto the pocket clip 17.

The lower end of the tube 13 has a solid shank 40 portion 18 which is reduced in diameter to form a shoulder 19 for the barrel 11 to butt against when it is threaded to the shank 18 as shown at 20 by engaging with a threaded collar 21 fixed to the inside of the barrel 11.

Before the solid top 14 is adhered to the transparent barrel 13 a plastic tubular guide sleeve 22 is placed within the barrel 13, extending from the bottom 23 of the top portion 14 to the bottom 24 of the transparent barrel 13.

After the plastic tubular guide sleeve 22 is properly positioned within the barrel 13 a gravity sliding sleeve 25 is placed over the tubular guide sleeve 22 so that it is then located between the guide sleeve 22 and the inside wall of the barrel 55 13.

The advertising element 26 is then inserted into the barrel 13 but inside of the tubular guide sleeve 22.

When the sleeve 22, slide 25, and element 26 are all properly positioned and assembled within the barrel 13, the barrel may or may not then be filled with oil before the cap or top 14 is adhesively secured to the barrel 13.

Referring to Fig. 3 it will be seen that the element 26, preferably comprises a cylindrical rod 27 having an object for display 28 and 29 on each end thereof, which may be integral with the rod 27 or adhesively or otherwise secured thereto.

The cylindrical rod 27 is preferably dimensioned to be co-axially guided by the inside wall of the guide sleeve 22 but permitted to rotate therein.

The objects 28 and 29 on each end of the rod 27 are faced in opposite directions and will have a slight movement between the inside end surfaces 23 and 24 when the writing instrument is alternately moved from either the writing position or the inverted position.

It will be observed that the gravity sleeve 25 is about as long as the distance between the base of the object to be displayed at one end of the rod 27 to substantially the top of the object to be displayed at the other end of the rod 27 so that when the gravity sleeve 25 slides in either direction the entire object at each end of the rod 27 will be alternately displayed in the windows 30 and 31.

In operating the device as shown in Figs. 1 and 2, it will be seen that when the instrument is in the writing position as shown in Fig. 1, the gravity sleeve 25 slides down to the juncture between the

barrel 11 and barrel 13 and uncovers the window 30 and displays the object 28, and when the instrument is inverted as shown in Fig. 2, the gravity sleeve 25 will slide towards the top 14 of the instrument and cover window 30 and uncover window 31 and display or reveal the object 29.

I claim:

A writing instrument comprising, a barrel containing a writing element, a transparent tubular barrel removably connected to said writing element barrel, an opaque gravity sliding sleeve guided by the inside wall of said transparent tubular barrel, a fixed transparent tubular guide member surrounding the inside wall of said opaque gravity sliding sleeve, and a cylindrical connecting rod guided by the inside wall of said transparent tubular guide member within said transparent tubular guide member having an object for display at each end thereof with each object being alternately displayed by the movement of said opaque gravity sliding sleeve.
